UNITED STATES PATENT OFFICE

GUSTAV S. LARSON, OF LOS ANGELES, CALIFORNIA

WEATHER STRIP

Application filed March 27, 1929. Serial No. 350,301.

This invention relates to improvements in appliances for excluding air, wind, and the elements from a room of a building and more particularly to weatherstrips.

5 One of the objects of this invention is to provide a simple, efficient and inexpensive weatherstrip designed to be applied to windows or doors which swing in a horizontal plane particularly.

10 Another object of this invention is to provide a weatherstrip designed to undergo movement to operative or inoperative relation as the window, door or other closure member moves to closed or open position or vice versa.

15 A further object of this invention is to provide means whereby the window, or door or closure member, movably associated in a suitable frame having an opening for ingress and

20 egress, may automatically operate the weatherstrip to make it perform the function of excluding the elements as soon as the closure member shall have closed the frame opening.

25 Another object of this invention is to provide a weatherstrip wherein the cost of manufacture and installation has been reduced to a minimum.

30 A still further object of this invention is to provide, in combination with a frame having an opening and a closure member hingedly connected thereto so as to bar and unbar the said opening weatherstrip means designed to make and break joint with the closure member accordingly as the member assumes a closed or an open position in said

35 frame. In making joint with the closure member the weatherstrip means will frictionally engage the member and completely exclude access of wind, cold, rain and the atmosphere into a room or building, and when the weatherstrip means breaks joint with the closure member the latter has moved to open position.

40 Another object of this invention is to provide weatherstrip means in conjunction with a French or casement window by virtue of the construction of which the weatherstrip means will project into the under edge of the window releasedly.

45 50 A still further object of this invention is to

provide a sheet metal stamping which is shaped to provide a weatherstrip designed to extend transversely beneath the window or door with which it is associated, and to engage, at the same time, with a window sill, 55 to bridge the space between the under edge of the window and the adjacent window sill.

In carrying out the details of construction of my invention I provide a swinging weatherstrip beneath the window or door, and locate it in a space between the under edge of the door or window and the adjacent sill; I provide means carried by the door or window engageable with the swinging weatherstrip to push the same from a normally inclined 60 inoperative position to a vertical operative position, whilst allowing the weatherstrip to drop to inactive position by gravity when the door or window is being opened.

65 With the above and other objects in view 70 my invention consists in the combination, arrangement and details of construction disclosed in the drawings and specification, and then more particularly pointed out in the appended claims.

75 In the drawings, wherein similar reference characters designate similar parts throughout the several views,

Figure 1 is a vertical sectional elevation 80 of a window frame showing the weatherstrip occupying an inclined inoperative position,

Figure 2 is a view similar to Figure 1 showing the window in partially closed position, pushing the weatherstrip progressively to 85 gradual open position.

Figure 3 is another view similar to Figure 1 but showing the window in fully closed position and the weatherstrip in open operative position.

90 Figure 4 is a front elevation of a window frame and sash showing details in section of the window sill and weatherstrip barring the same.

Figure 5 is an end view of the weatherstrip.

95 Figure 5^a is an end view of the bracket to be described, and

Figure 6 is a plan view of the said bracket shown in Fig. 5^a.

100 Referring to the drawings, which are merely illustrative of my invention there is dis-

closed a window frame with a French or casement type of window, altho it is understood that the same arrangement can be made to apply to doors and door frames as well. The window frame is designated broadly A and designed to fit the opening C in this frame is a window sash 10 of approved design and construction hinged as at C' so as to be capable of swinging in a horizontal plane upon said hinges. The under edge of the window is designed to be spaced above the threshold or stool E of the window frame which projects outwardly of the exterior face of the window frame, being surmounted upon a window sill 15 B in the usual manner. There is thus provided the space M between the lower edge of the window 10 and the adjacent threshold bead D secured on the threshold flush with the inside face of the window 10 when the latter is closed. The bead D extends transversely of the opening C of the frame and has a forward downwardly inclined wall 21 disposed along a midposition of the threshold E. Formed upon the underside or under edge of the window 10 is a groove 15^a and a sheet metal bracket formed angle-iron in shape, has its arm 17 secured by suitable fasteners 18 into this groove so that its other arm 16 extends at right angles in depending relation from the arm 17; it will be seen that the arm 16 projects below the bottom plane of the groove 15^a, and that the edge of the bracket in the notch is spaced away from the exterior wall of the groove 15^a to provide between itself and the said notch wall a slit 15. Formed transversely of the bead D is a narrow slit 20 shown in Figure 4 and in this slit is designed to slide the depending arm 16 of the bracket as the window sash 10 moves from closed or open position or vice versa.

I will now describe the weatherstrip which I have designed. It is formed from sheet metal preferably and consists of the elongated plate 12 made of a length to extend across the full width of the window frame A and has a right angular top offset 13 terminating in an angular flange 14 extending the full length of the weatherstrip. This weatherstrip plate 12 is designed to rest with its bottom edge upon the window sill B, being held against displacement from the threshold thereof by any suitable means. I prefer to secure a fastener or wood screw 19 in a manner to pass thru the weather strip plate 12, and be secured into the threshold, the plate being loosely mounted upon this screw so as to have play enough to hingedly swing to a vertical operative position shown in Figure 3 to an inclined inoperative position shown in Figure 1.

It will be seen from Figure 1 that when the weatherstrip inclines in inoperative position that plate 12 rests upon the forwardly inclined surface 11 of the forward end of the threshold E, with its offset 13 projecting over the stool and with its marginal flange 14 in-

clining in flat contact with the inclined wall 21 of the bead D. In this position the weatherstrip is supported on a bias with no part of its makeup projecting above the plane of the bead D. The window sash 10 has been open to enable this weather-strip to occupy this position.

When it is now desired to close the window to bar the frame opening, the window sash 10 is moved on its hinges and brought into position over the threshold E of the frame A. From Figure 2 it will be seen that the depending arm 16 of the bracket will be free to ride in slit 20 of the bead D. Due to the fact that the flange 14 of the bead closes the slit 20, as shown in Figure 1 the arm 16 will engage this flange, push the same forwardly, as it rides thru the slit 20, thus tilting the weatherstrip outwardly and upwardly and then makes flange 14 of the plate 12 of the weatherstrip enter the groove of the window sash, whence the flange begins to position itself in slit 15 of this groove, while the weatherstrip is about to assume the vertical operative position shown in Fig. 3.

In this vertical position of the weatherstrip it will be observed that plate 12 bridges the space between sill and the under edge of the sash so no air, rain or atmosphere can gain access into the room. In forcing this weatherstrip to assume a vertical position it makes joint with the sash with a press fit, so that the offset 13 engages the under edge of the sash to enable the upstanding flange 14 to project into the groove 15^a of the sash; it will thus be seen that the reentrant angle of the weatherstrip provides a double check against the admission of the elements into the room as even if it gets thru between offset 13 and the adjacent surface of the sash it would have to pass upwardly between flange 14 and the adjacent wall of the groove. The flange 14 is preferably disposed at an angle slightly less than a rightangle where it joins the offset 13 of the weatherstrip so with all parts as shown in Figure 3 the flange makes a press fit with the mentioned wall of the groove, thus effectively excluding wind, rain and the like.

When the sash 10 is moved to open position, there is room in the slit 15 of the groove for the flange 14 to work itself loose as shown in Figure 2, so as the sash recedes from the flange and plate 12 flange 14 leaves the sash groove and under influence of gravity the weatherstrip falls down upon the threshold and bead and is idle again as shown in Figure 1. From the foregoing it will be seen that the weatherstrip has a floating connection whereby it can open and close, opening to vertical position when the sash closes and closing to inclined or biased position when the sash opens.

I do not mean to restrict myself to the exact details of construction disclosed in the draw-

ings but intend to cover all variations falling within the purview of the appended claim.

What I claim and seek protection on is as follows:—

5 In combination with a rabbeted casement or outside door frame, a sash or door hingedly mounted on said frame, in inswinging position, a groove in the lower edge of the bottom rail of the sash or door and a metal bracket secured to the bottom of the groove with its 10 depending arm extending down below the bottom of the sash or door, a movable weather-strip device which consists of a longitudinal sheet metal plate having a rightangular 15 marginal flange with a reentrant outstruck marginal strip formed integrally upon the flange at a slight acute angle, extending the full distance between the jambs and retained in place by resting against the rabbets of 20 the jambs with the lower edge of the plate when in inoperative position and with the flat surface of the plate when in operative position forming a flush surface with the outside face of the bottom rail of the sash or door, a 25 horizontal contact with the lower edge of the sash or door and a vertical contact with the outer vertical wall of the groove in the lower edge of the bottom rail of the sash or door, when sash or door is closed.

30 In witness whereof he has hereunder set his hand this twenty-third day of March, 1929.
